UNITED STATES PATENT OFFICE.

GEORGE W. SMITH, OF BOSTON, MASSACHUSETTS.

HAND DRILLING-MACHINE.

SPECIFICATION forming part of Letters Patent No. 279,032, dated June 5, 1883.

Application filed December 1, 1882. (No model.)

To all whom it may concern:

Be it known that I, GEORGE W. SMITH, a citizen of the United States, residing at Boston, in the county of Suffolk and State of Massachusetts, have invented certain new and useful Improvements in Hand Drilling-Machines; and I do hereby declare that the same are fully described in the following specification and illustrated in the accompanying drawings.

5 This invention relates to improvements in hand drilling-machines, and is carried out as follows, reference being had to the accompanying drawings, on which—

Figure 1 represents a side elevation of my improved drilling-machine. Fig. 2 represents a central longitudinal section of the same, and Fig. 3 represents a section on the line A. B, shown in Fig. 1.

Similar letters refer to similar parts on the different parts of the drawings.

a represents the spindle of the drilling-machine, having a chuck or socket, a', in one end to receive the drill, and having a feeding-screw, a'', in the other end to cause the drill to be fed forward in the usual way by means of a rod or wrench. The spindle a is provided with a fixed collar, a''', made in one piece with the spindle, and is also provided with a removable collar, b. Between the collars a''' and b is arranged 25 the hollow hub c' of the handle c in such a manner that it surrounds the spindle a. The hub c' is provided with tapering recesses c'' c'' c'', containing rollers d d d, loosely journaled, one on each of the axles e e e, and also with 30 projections c''' c''' c''', against which the rear ends of the guide-rods f f f have their bearings. The guide-rods f f f have their forward ends projecting through perforations in the center of the axles e e e, and are provided with spiral 35 springs f' f' f' surrounding them and tending to force the axles, with their rollers, into the narrowest parts of the recesses c'' c'' c'' until the rollers press against the spindle a and the hub c' of the handle c. The rollers d d d are

made with tapering bearings d' d' for the axle 45 e e, so as to allow the rollers to adapt themselves to the surfaces against which they are pressed.

The operation of my improved drilling-machine is as follows: When the machine has 50 been placed in position for drilling, it will be seen that by moving the handle c in the direction indicated by the arrow in Fig. 3 the handle c, hub c', rollers d d d, and spindle a become firmly attached to each other, and for the 55 time being they form, as it were, one single piece. Now, if you reverse the direction of the movement of the handle c, the rollers d d d are instantly released from the hub c', and allow the hub to be revolved around on the spindle 60 a without moving the spindle.

The advantages of my improvements are: It can be operated without noise. There can be no lost motion, as the rollers are instantly and firmly held between the hub and spindle as 65 soon as the handle is moved in the direction of the arrow in Fig. 3. All operating parts are covered, so that no dirt can get to them and clog them. It is very strong and not liable to be broken.

Having thus fully described the nature, construction, and operation of my invention, what I wish to secure by Letters Patent and claim is—

In a hand drilling-machine, the combination 75 of the spindle a, with its chuck or socket a', feeding-screw a'', and collars a''' b, with a handle, c, having hollow hub c', provided with cam-recesses c'' c'' c'', containing rollers d d d, axles e e e, guide-rods f f f, and springs f' f' f', 80 and also provided with projections c''' c''' c''', as and for the purpose set forth and described.

In testimony whereof I have affixed my signature in presence of two witnesses.

GEORGE W. SMITH.
